UNITED STATES PATENT OFFICE

2,441,322

ELECTRIC CAN OPENER

John Jager, Chicago, Ill.

Application October 18, 1946, Serial No. 704,051

5 Claims. (Cl. 30—4)

1

This invention relates to can openers, and more particularly to a can opener which may be operated by electricity.

It is an object of the present invention to provide an electric can opener which, as a can is placed under the cutting tool and raised by a lever into cutting position, will automatically cut off the can top without any added effort on the part of the housewife, or other person, using the device.

It is another object of the invention to simplify the operation of opening a can, place less strain on the housewife while opening the can, and avoid cutting of hands when holding the can in place for being opened.

According to the invention, the can is placed upon a revolvable table which is vertically adjustable. The operator will press down upon a lever to elevate the revolvable table and bring the can top into engagement with a cutter and rotating element adapted to grip the rim of the can to rotate the same while it is being cut. At the same time that the can is brought upwardly, a switch is automatically operated by the top of the can and a motor is set in operation to drive the rim-rotating element to cause the top of the can to be cut. The motor and the cutting and rim-rotating tool are carried on a vertically adjustable frame. This frame can be adjusted for different size cans by a hand device located upon the side of the main support.

For other objects and for a better understanding of the invention, reference may be had to the following detailed description taken in connection with the accompanying drawings, in which:

Figure 1 is a vertical cross-sectional view taken through the entire mechanism.

Figure 2 is a vertical cross-sectional view taken through the mechanism from a different direction, and as viewed generally along the line 2—2 of Figure 1, and looking in the direction of the arrows thereof.

Figures 3 and 4 are respectively transverse cross-sectional views taken along the line 3—3 of Figure 2, and looking respectively in the opposite direction indicated by the arrows, the view of Figure 3 being an enlarged fragment.

Figure 5 is an enlarged fragmentary sectional view taken on the line 5—5 of Figure 2 showing the relation of the cutter and rim-engaging tools with the can.

Figure 6 is an enlarged fragmentary sectional view of the cutter and rim-engaging tool in operative relation with the can of Figure 2.

2

Referring now to the figures, 10 represents a base having an upstanding housing 11 including a horizontal portion 12 through which is extended a shaft 13 carrying a revolvable supporting plate 14 for a can 15. The shaft 13 is vertically guided in a frame 16 for vertical adjustment by a gear-adjusting mechanism 17. The gear mechanism 17 includes a large gear 18 to which is connected an operating lever 19 extending exteriorly of the mechanism. As downward pressure is applied to the lever 19, the gear 18 is rotated in a counter-clockwise direction, as viewed in Figure 1, and this gear will in turn drive in a clockwise direction a small gear 21 having a cam 22 secured thereto and adapted to abut the bottom of the shaft 13. The frame 16 is in turn connected to the base 10 for horizontal adjustment whereby to adapt the mechanism for cans of different diameters. To provide for this horizontal adjustment, there is provided a guideway 23 on the base 10 into which projections 24 extend so as to be guided by the part 23. After the can has been opened, the lever 19 is released and the can and supporting plate 14 will be permitted to be lowered to its original position. Extending upwardly from the horizontal portion 12 of the housing 11 is a vertical portion 25 adapted to house and guide a vertically adjustable housing 26 which carries an electric motor 27, rim-engaging tools 28 and 29, a cutter element 31 and an automatic switch 32. The rim-rotating tool 29 is driven by reduction gearing 33 from the motor 27. This reduction gearing is retained in a bracket portion 34 of the vertical housing 26 and one of its shafts 35 is retained against lateral displacement by a depending lug 36 extending downwardly from the top of the portion 26.

The rim-rotating tools 28 and 29 have spiral groove formations on their surfaces and are so arranged as to receive and retain the rim of the top portion of the can in such manner as to effect its rotation as they are operated by the electric motor 27. As the can 15 is elevated by the revolvable plate 14, the top thereof is punctured by the cutting tool 31 carried on the bracket portion 34. Thus, as the can is rotated, the cutting tool will make a continuous cut about the periphery of the top of the can. Simultaneously with the lifting of the can 15, the automatic switch mechanism 32 has its plunger 37 engaged by the top of the can to close the switch contact 38, whereby to close a circuit directed to the motor and to automatically start its operation. No further effort is required by the operator than that of lowering the operating lever 19

to raise the can 15 into place. The back of the can 15 is guided by a grooved portion 41 on the main housing 11. The can 15 is placed upon the rotating plate 14 until it engages the grooved portion 41.

In order to adjust the mechanism for different heights of cans, there is provided within the base housing 11, and particularly within the vertical portion 28 thereof, an elevating device 43 adapted to be operated by a hand wheel 44 extending exteriorly of the portion 28 and at the side of the mechanism that the operating lever 19 is extended. This mechanism 43 further includes bevel gears 45 and 46 and a vertically extending threaded shaft 47 adapted to work in an internally threaded transverse portion 48 integral with the interior of the vertically adjustable part 28. The gear 46 is fixed to the vertical shaft 47 and the gear 45 is fixed to a shaft 49 carrying the hand wheel 44. The threaded shaft 47 is supported at its bottom 10 against lateral displacement by a retaining portion 51 of the base 10.

In order to retain the vertical portion 28 against rotational displacement within the portion 28, there is provided a radially inwardly extending lug 54 on the portion 28 which extends into an elongated guide slot 55 on the portion 28.

While various changes may be made in the details of construction, it shall be understood that such changes shall be within the spirit and scope of the present invention as defined by the appended claims.

I claim:

1. An electric can opener comprising a base having a vertically extending housing, a vertically adjustable part extending into the base housing to be guided thereby and adapted to be adjusted vertically upwardly therefrom, said housing part having an electric motor, gear reduction mechanism, rim-rotating tools connected with the motor through the gearing, a cutting tool on the adjustable portion adjacent to the rim-rotating tools, and an elevating platform on which a can may be rested and elevated into place between the rim-rotating tools and to initially puncture the top of the can, and means for starting the operation of the electric motor.

2. An electric can opener comprising a base having a vertically extending housing, a vertically adjustable part extending into the base housing to be guided thereby and adapted to be adjusted vertically upwardly therefrom, said housing part having an electric motor, gear reduction mechanism, rim-rotating tools connected with the motor through the gearing, a cutting tool on the adjustable portion adjacent to the rim-rotating tools, an elevating platform on which a can may be rested and elevated into place between the rim-rotating tools and to initially puncture the top of the can, means for starting the operation of the electric motor, said means for starting the operation of the motor including a switch adapted to be operated by the top of the can as it is brought upwardly into place for engagement with the rim-rotating tools and in engagement with the cutter whereby the cutting operation will be effected automatically as the can is raised into place.

3. An electric can opener comprising a base having a vertically extending housing, a verti-

cally adjustable part extending into the base housing to be guided thereby and adapted to be adjusted vertically upwardly therefrom, said housing part having an electric motor, gear reduction mechanism, rim-rotating tools connected with the motor through the gearing, a cutting tool on the adjustable portion adjacent to the rim-rotating tools, an elevating platform on which a can may be rested and elevated into place between the rim-rotating tools and to initially puncture the top of the can, means for starting the operation of the electric motor, said vertically adjustable portion containing the motor and the cutting tool having an elevating device connected between it and the base, said elevating device having a manually operable hand wheel extending exteriorly of the base housing for vertical adjustment whereby the vertical portion can be adjusted to operate upon cans of different heights.

4. An electric can opener comprising a base having a vertically extending housing, a vertically adjustable part extending into the base housing to be guided thereby and adapted to be adjusted vertically upwardly therefrom, said housing part having an electric motor, gear reduction mechanism, rim-rotating tools connected with the motor through the gearing, a cutting tool on the adjustable portion adjacent to the rim-rotating tools, an elevating platform on which a can may be rested and elevated into place between the rim-rotating tools and to initially puncture the top of the can, means for starting the operation of the electric motor, and means for elevating the can-supporting platform comprising an axially adjustable shaft, a cam adapted to engage the bottom of the shaft to elevate the same, gearing connected with the cam, and an operating lever extending exteriorly of the base housing for effecting rotation of the gearing and the cam whereby to elevate the can-supporting platform.

5. An electric can opener comprising a base having a vertically extending housing, a vertically adjustable part extending into the base housing to be guided thereby and adapted to be adjusted vertically upwardly therefrom, said housing part having an electric motor, gear reduction mechanism, rim-rotating tools connected with the motor through the gearing, a cutting tool on the adjustable portion adjacent to the rim-rotating tools, an elevating portion on which a can may be rested and elevated into place between the rim-rotating tools and to initially puncture the top of the can, means for starting the operation of the electric motor, means for effecting the elevation of the can-supporting platform including a lever extending exteriorly of the base housing, and means for securing the can-supporting platform and the elevating means upon the base for horizontal slidable adjustment whereby to alter the position of the can-supporting platform to adapt the same for use with cans of different diameters.

JOHN JAGER.
